GEOMETRICAL INSTRUMENT

Henry E. Maupin, Dayton, Ohio

Application August 9, 1941, Serial No. 406,234

3 Claims. (Cl. 77—69)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to geometrical instruments and more particularly to rotary cutters. This invention has as its objects the provision of a geometrical instrument that is extremely rugged, one that may be accurately adjusted to mark or cut a hole of a given diameter, one that has a wide range of adjustment characterized by the feature that the marker or cutter may be moved to a position very close to the pilot drill, and one in which the marker or cutter may be replaced without changing the adjustment of the device. Further objects and advantages of the invention will become apparent as this description proceeds.

Briefly, the instrument that is the preferred embodiment of this invention comprises a U-shaped sweep that carries a cutter bit at the closed end of the U. The outermost side walls of the U-shaped sweep member are tapered and a body member is provided that has inner walls correspondingly tapered as well as in contact with said side walls. The body member is adjustable with respect to the U-shaped sweep member in order that the pilot drill may be positioned at any distance from the cutter bit within the range of operation of the device. When it is desired to use the tool in a given position, the U-shaped sweep bars are forced downward to exert great pressure on the inner side walls of the body member and this holds the sweep member securely in place.

In the drawing, Figure 1 is a perspective view of my instrument. Figure 2 is a vertical sectional view taken through the center of the pilot drill and transverse to the bars of the elongated U-shaped sweep member whereas Figure 3 is a vertical sectional view taken through the center of the pilot drill and in a plane parallel to the bars of the elongated U-shaped sweep member. Figure 4 illustrates in perspective certain details of the means that holds the pilot drill as well as forces the bars against the body member. Figure 5 is a bottom view of the device of my invention showing graduated scales that enable an accurate setting of my instrument to be made.

In the drawing there is shown a U-shaped sweep member 16 with a cutter bit 10 at the closed end thereof. The cutter bit 10 may be used for cutting a hole or merely marking a circular line of a given diameter and may be replaced by any other form of cutting and/or mark-

ing tool, for example a pencil, without departing from the broadest aspects of this invention. The cutter bit 10 is held rigidly in place by a suitable lock screw 17, and may be readily replaced without affecting the adjustment of the instrument. The outer side walls of the two parallel bars, that comprise the U-shaped sweep 16, are tapered at an angle of about fifteen degrees from the vertical throughout their respective lengths. The inner walls of the elongated bars 16 are, however, parallel as well as vertical. A body member 11 has inner walls tapered at an angle conforming to the taper of the outer side walls of member 16 and in contact therewith. The body member 11 has rigidly attached thereto a chucking shank 21 having an internal left hand thread. A cylindrical member 19 has a flange thereof 15 together with another cylindrical portion 20. The flange 15 and the portion 20 fit into a cavity 20 in the body member 11 and the pilot drill 18 extends through the centrally located hole in cylindrical member 19 and is fastened to that member by the pilot drill lock screw 14. Located above the member 20 is a knurled adjusting member 13 which is rigidly fastened to the left hand threaded screw 12 so that when the knurled member 13 is turned manually a great pressure is exerted downwardly on the portion 20 and hence upon the flange 15. This forces the flange 15 against the bars 16 and causes these bars to contact their complementary surfaces of body 11 under great pressure. To move the pilot drill 18 with respect to the cutter bit 10, it is simply necessary to loosen the knurled member 13 and then move the bars 16 in one direction or the other to the desired new position which may be determined by reference to the graduated scales 22 and 23 shown in Figure 5. When the new setting has been accurately determined by reference to the scales, the knurled member 13 may again be tightened to lock the device in its desired position.

The scales 22 and 23 may be graduated in any suitable increments that will effect a vernier adjustment, for example the scale 22 may have a graduation mark every $\frac{1}{40}$ of an inch and the scale 23 may have graduation marks every $\frac{1}{25}$ of an inch each side of the zero mark thereof.

To use my invention, the knurled member 13 is loosened and the slidable bars 16 moved in or out of body member 11 until the scales show the desired size of hole will be cut by the device. The pilot drill 18 is then positioned on the work piece at a point where it is desired to have the center of the hole to be cut. The chuck of a

brace is clamped over the portion 21 of housing 11 and the entire device, including the pilot drill 18 and the cutter bit 10 is rotated by the brace. The cutter bit then cuts a hole in the work piece 24. Due to the rigid support for the cutting tool 10, the vibrations and usual chatters of the tool are almost completely eliminated and this prevents the so-called "digging-in" of the cutter bit 10. The cutter bit 10 rotates smoothly and in synchronism with the pilot drill 18 until it finally cuts a slot completely through the work piece 24. Hence it is possible to not only obtain a quick accurate adjustment of my instrument before beginning to cut a hole but it is possible to cut the hole with great speed and accuracy 15 due to the absence of chatter.

I claim to have invented:

1. A rotary cutter tool comprising a body member having a base and defining a slot therethrough of uniform cross-section throughout the length thereof; said slot having a narrow portion of its cross-section at the base of the body member and said slot having straight sides tapering away from each other as the distance from said base increases; an elongated U-shaped sweep member located so the plane of the U is parallel to the base of the body member; said U-shaped sweep having outer side walls that fit to and conform in taper with the said tapering walls of said slot; said U-shaped sweep having a top surface located in a plane parallel to said base and a bottom near said base; a drill carrying member fitting snugly between the bars of said U-shaped sweep and having a flange located on said top surface; a pilot drill carried by said member, having a supporting portion located in said member near the flange, and a drill portion extending outwardly from the supporting portion and past the plane of said base; means attached to said body member to control the position of said drill carrying member and retain the same in fixed relation with the body member; a tube extending above the body member, in fixed relation thereto and having threads on the inside of the tube; means for exerting a force on said flange comprising a threaded rotatable screw member operatively cooperating with said threads inside said tube and operable to be rotated to exert great pressure downwardly

5 and force said flange in contact with said top surface, whereby said screw member may also be rotated to release said pressure and enable adjustment of the device, and a cutter bit mounted at the closed end of said U-shaped sweep member and projecting therefrom in a plane parallel to the pilot drill and in the same direction as the pilot drill projects from said drill carrying member.

10 2. A geometrical instrument comprising a body member having an internal slot the sides of which relatively taper away from each other as the distance from one surface of the member increases; a second member positioned in said slot and having side walls conforming to the taper and shape of the sides of said slot; means to engage the article to be worked comprising a pilot to act as a centering tool of the instrument and located in fixed relation to one of said members and extending away from said surface with its pivot point located in the direction away from said surface that planes of the tapering sides converge, and a marker attached to the other of said members and extending therefrom parallel to the pilot; and manually controlled means located on said body member operable to move into contact with said second member and exert a large compression on the same to force the same toward said surface, whereby, to clamp said members together; said manually controlled means also being operable to release the large force between said members, whereby they may be moved relative each other to effect various distances of separation between said pilot and said marker.

20 3. A geometrical instrument comprising first and second members one of which passes through the other; the outside member having its inner side walls relatively tapered and the inside member having its outer side walls substantially similarly tapered; means cooperating with said members operable to either force said tapered surfaces in contact under great pressure, and thereby hold the same in fixed relation to each other, or to release the pressure therebetween, whereby to permit the members to be moved relative to each other; a pilot carried by the first member; and a marker carried by the second member.

HENRY E. MAUPIN.
